ors to American Locomotive Company, New
York, N. Y., a corporation of New York

Application August 6, 1943, Serial No. 497,660

7 Claims. (Cl. 309—19)

This invention relates to pistons, and more particularly to an internal combustion engine piston having a rotative body.

An object of the present invention is to provide an improved piston having a rotative body.

A further object is to provide a piston as aforesaid, having a rotative body and a separate non-rotative wrist pin carrier, and means connecting the body and carrier adapted to withstand the forces to which the piston is subjected.

A further object is to provide a piston as aforesaid provided with improved cooling and lubricating means.

Other and further objects of this invention will appear from the following description, the accompanying drawings and the appended claims.

Referring to the drawings forming a part of this application, Figure 1 is a central vertical section taken on the line I—I of Fig. 2, showing the piston of the present invention and a portion of the cylinder and connecting rod associated therewith, parts being shown in full; Fig. 2 is a section on the line II—II of Fig. 1; Fig. 3 is, at the right, a section on the line III—III of Fig. 1, and at the left, an inverted plan, of the piston; Fig. 4 is a plan view of the wrist pin carrier; Fig. 5 is a section on the line V—V of Fig. 4; Fig. 6 is a view similar to Fig. 1, taken on the line VI—VI of Fig. 7, of a modification of the present invention; Fig. 7 is a section on the line VII—VII of Fig. 6; Fig. 8 is a section on the line VIII—VIII of Fig. 7; Fig. 9 is an elevation of the wrist pin carrier of Fig. 6; Fig. 10 is, at the right, a plan of Fig. 9, and, at the left, a section on the line X—X of Fig. 9; Fig. 11 is an inverted plan of the piston of Fig. 6, partly broken away; Fig. 12 is an inverted plan of the retainer of Fig. 1 with certain of the associated parts shown in dot and dash lines; and Fig. 13 is an enlarged fragmentary section of the bottom portion of the skirt similar to that shown at the right in Fig. 1.

Referring more particularly to Figs. 1—5 of the drawings, only a portion of the cylinder 4 of the internal combustion engine is shown. In the cylinder is disposed a composite piston 2 mounted on a connecting rod 3.

The piston 2 has a rotative piston body 4 including a thin-walled head 5 and a thin-walled skirt 6. Piston rings 7 are disposed in piston ring grooves 8 in the external face of the skirt. Two oil-scraping rings 9, which wipe excessive oil off the inner face of the cylinder are disposed in

grooves 9' (the grooves being best shown in the enlarged view, Fig. 13) in the bottom portion of the skirt, grooves 9" draining back to the engine crank case (not shown) by means of bores 10. An annular transverse wall or flange 11 extends radially inwardly from the inner face of the skirt 6 and is reinforced by webs 12 formed integral with the flange and with the inner face of the skirt above the flange. Immediately beneath the flange 11, which has a flat transverse bottom face 13, the skirt is thick, providing a rim 14 having an inner cylindrical face 15 concentric with the piston body 4. The bottom portion of the skirt is also thick, providing a rim 16 having an inner cylindrical face 17 in line with face 15. Immediately below the face 17, four cylindrical tracks or grooves 18 are formed in the inner face of the skirt for a purpose presently to appear. Intermediate the faces 15 and 17 the skirt is thickened providing another rim 19 having an inner cylindrical face 20 in line with faces 15 and 17. The hollow interior of the piston body between the flange 11 and the grooves 18 forms a housing portion.

The piston further includes a wrist pin carrier 21, disposed within the housing portion of the body 4, which is of general cylindrical external shape and has a flat top face 22 in engagement, by means of a shim 23, with face 13, and further has a top cylindrical side portion 24 in engagement with the face 15, and a bottom cylindrical side portion 25 in engagement with face 17. Carrier 21 is secured in this position by a retainer formed of two segments 26, each of which has lateral tongues 27 fitting in grooves 18. Segments 26 are secured in place by tap bolts 30 extending through orifices 31 in the segments and being screwed into threaded orifices 32 in carrier 21. All of the engagements between the carrier and piston body have sufficient freedom to permit sliding rotative movement therebetween.

The carrier further has aligned wrist pin bearings 33 provided with bushings 34, and, at right angles thereto, aligned weight-reducing openings 35. Lubricating grooves 36 are formed in the inner face of the bushing. A lubricating and cooling oil receiver 37 is formed integral with the face 22 of the carrier. The receiver has a central passage 38 funnel-shaped transversely of the wrist pin bearing. The receiver, at the opposite inclined ends thereof, has but a single wall 39 (Fig. 2), but, at right angles thereto it has, at each side, an inner wall 40 and an outer spaced wall 41 (Fig. 1). An orifice 42 is formed

in each of the outer walls 41. The walls 39 and 41 are contiguous with the face 22. The connecting rod 3 is provided with a boss 43, having a top face 44 curved concentrically with the axis of the wrist pin bearings 33, and the receiver 37 at its bottom, formed by the bottom faces 45 and 46 of walls 39 and 40, respectively, is curved similarly to the curvature of face 44 and slightly spaced therefrom.

The connecting rod 3 is conventional in structure and is therefore only shown fragmentally. It has a wrist pin bearing 47 in its upper end, provided with a bushing 48 secured therein against rotation by a lock screw 49. It further has a central longitudinal bore 50 adapted to be connected at the bottom of the connecting rod with a source of lubricating oil under pressure (not shown) and opening at its top into the funnel-shaped passage 38. Bore 50 has a portion below the wrist pin bearing 47 and a portion above the wrist pin bearing, the latter passing through boss 43, bore 50 thereby being intersected by the bearing 47. The two portions of bore 50 are connected around the bushing 48 by a groove 51 which is connected, by bores 52, with lubricating grooves 53 formed in the inner face of bushing 48.

A hollow wrist pin 54, disposed for free rotation in bushings 34 and 48, secures the connecting rod to the carrier. The wrist pin ends 55 are curved spherically concentric to the inner face 20 of the rim 19 which the ends are adapted to engage to prevent lateral displacement movement of the wrist pin.

Before assembling the parts of the piston together, the connecting rod is inserted into the hollow interior of the carrier, and the wrist pin is slid into the bushings 34 and 48 through a side of the carrier. Then the carrier, with the connecting rod secured thereto, is moved into the piston body until the face 22 engages the face 13 by means of the shim 23. The segments 26 are then inserted in the body 4 beneath the carrier 21 so that the tongues 27 are in their respective grooves 18, and the orifices 31 and 32 of the segments and carrier respectively are in alignment. The tap bolts 30 are then screwed into place, securing the parts of the piston together.

Piston 2 is especially adapted for employment in a four-cycle engine wherein the suction stroke imposes a force on the means connecting the wrist pin carrier to the piston body, in the present instance on the tongues 27 of the segments and on the portion of the body 4 containing the grooves 18. On the power stroke, the force is taken by the flange 11. The flange 11, the body adjacent the grooves 18, and the segments are made sufficiently strong to withstand the forces to which they are subjected. Webs 56 formed integrally with the top and side walls of the carrier strengthen it around the receiver 37. It will be obvious that piston 2 will work as well in other cycle engines, for instance in a two-cycle engine wherein theoretically all the forces will be taken by the flange 11.

The lubricating and cooling cycle of the piston is as follows:

Oil under pressure is pumped upwardly through the bore 50 and into groove 51. Some of the oil lubricates bushing 48 through the bores 52 and grooves 53. The remainder of the oil passes into the funnel-shaped passage 38, from which it overflows into a chamber 57 formed by the hollow interior of the piston body above the

flange 11. This oil is splashed generously over the adjacent surfaces of the piston head, skirt and carrier, cooling them. Passage 38 forms the inlet of the cooling chamber 57 and the outlet is formed by the orifices 42 in the outer walls 41 of the receiver 37. The oil enters the space between the walls 40 and 41 by means of the orifices 42 and flows downward over the surfaces of the wrist pin and connecting rod and into the grooves 36 of bushings 34, lubricating same. Some oil in the cooling chamber 57 also leaks through the sliding fit between the flange 11 and the face 22 and between the portion 24 and face 15, and the oil draining from the portion 24 and from the bushings 34 lubricates the portion 25, face 17, the tongues 27 and the grooves 18. Thus all engaging faces between the piston body and carrier are well lubricated and cooled, assisting in floating the piston body on the carrier for rotative movement. Openings 35 prevent accumulation of oil between the carrier and piston body.

The piston body is of relatively thin construction, as the thick wrist pin bosses are part of the carrier, and therefore expansion and contraction in the piston body is more uniform than in conventional one-piece pistons. Also, due to the ability of the piston body to rotate, more even transmission of heat from the piston head 5 to the cooling fluid is effected. Similarly, the carrier with its wrist pin bosses, being separated from the piston body, is not subjected to severe heat transfer therefrom and heat stresses in the carrier are also avoided. Uneven expansion and contraction of the carrier, if it occurs, due to heavy metal concentration, does not affect the piston body, due to the freedom between these members. Thus the necessary clearance between the cylinder and the body is small.

A modification of the present invention is shown in Figs. 6-11. In this embodiment parts corresponding to similar parts in the embodiment of Figs. 1-5 will be designated by the same reference numeral with an accent added, and only a brief description thereof will be given.

The piston 2' has a thinner head 5' than the piston 2 and therefore it is desirable to support the piston head 2' on the wrist pin carrier 21'. The differences in structure between the two embodiments shown in the drawings are caused by this difference in the thickness of the piston heads. In general piston 2' is like piston 2, but instead of the flange 11, it has an annular wall or flange 11' formed by the bottom of a hollow boss 58 which depends from the head 5'. The boss 58 has an orifice 59 in its bottom and four orifices 60 in its side walls.

The carrier 21' is secured in the piston 2' similarly to the manner in which the carrier 21 is secured in the piston 2, the carrier 21' having an upper face 22' engaging, by means of a shim 23', the bottom flat face 13' of flange 11'. The carrier 21' has a receiver 37' provided with a central passage 38' which opens through the orifice 59 for flow of cooling and lubricating oil into the interior of the boss 58, and therefrom through the orifices 60 into the chamber 57' between the carrier 21' and the adjacent walls of the piston. The oil leaves the chamber 57' through orifices 42' in the walls 41' of the carrier.

It will be apparent from the above brief description of the embodiment of Figs. 6-11 how this embodiment differs from the embodiment of Figs. 1-5, and no further description thereof is deemed necessary.

While there have been hereinbefore described approved embodiments of this invention, it will be understood that many and various changes and modifications in form, arrangement of parts and details of construction thereof may be made without departing from the spirit of the invention, and that all such changes and modifications as fall within the scope of the appended claims are contemplated as a part of this invention.

The invention claimed and desired to be secured by Letters Patent is:

1. A piston comprising a body having a hollow cylindrical interior housing portion and an internal transverse wall at the inner end of said housing portion; a hollow cylindrical wrist pin carrier disposed in said housing portion, having a face at its inner end slidably engaging the outer face of said wall; and a segmental retainer bolted to said carrier at the outer end thereof, said retainer and body having a slidably tongue-and-groove-like connection whereby said body is rotatably mounted on said carrier.

2. A piston comprising a body member having a hollow cylindrical interior housing portion and an internal transverse annular flange at the inner end of said housing portion; a hollow cylindrical wrist pin carrier member disposed in said housing portion, having a transverse face at its inner end slidably engaging the outer face of said flange and a receiver providing a passage for a cooling and lubricating medium extending inwardly from said transverse face through the center of said annular flange; and a retainer adjacent the outer end of said carrier member secured to one of said members and slidably engaging the other of said members whereby said body member is rotatably mounted on said carrier member.

3. A piston comprising a hollow body member having a head, a skirt and an internal transverse annular flange extending radially inwardly from the inner face of said skirt at a portion thereof spaced outwardly from said head; a hollow cylindrical carrier member disposed in said body member having a bore for a wrist pin, a transverse face at its inner end slidably engaging the outer face of said flange and a receiver providing a passage for a cooling and lubricating medium extending inwardly from said transverse face through the center of said annular flange, said carrier member and flange cooperating to provide in said hollow interior of said body member inwardly of said flange, a chamber for said cooling and lubricating medium, said passage being open at both ends forming an inlet for said chamber; and a retainer adjacent the outer end of said carrier member, secured to one of said members and slidably engaging the other of said members whereby said body member is rotatably mounted on said carrier member.

4. A piston comprising a hollow body member having a head, a skirt and an internal transverse annular flange extending radially inwardly from the inner face of said skirt at a portion thereof spaced outwardly from said head; a hollow cylindrical carrier member disposed in said body member having a bore for a wrist pin, a transverse face at its inner end slidably engaging the outer face of said flange and a receiver providing a passage for a cooling and lubricating medium extending inwardly from said transverse face through the center of said annular flange, said carrier member and flange cooperating to provide in said hollow interior of said body member inwardly of said flange, a chamber for said cooling and lubricating medium, said passage being open

5 at both ends forming an inlet for said chamber, and having opposed sets of double spaced walls, the outer wall of each set being orificed and opening into said chamber, forming outlets for said chamber, the space between said walls of each set communicating with said bore; and a retainer adjacent the outer end of said carrier member, secured to one of said members and slidably engaging the other of said members whereby said body member is rotatably mounted on said carrier member.

10 5. A piston comprising a hollow body member having a head and a skirt; a hollow cylindrical carrier member disposed in said body member, having a bore for a wrist pin, a transverse inner wall and a receiver providing a passage for a cooling and lubricating medium open at its outer end to said bore and open at its inner end through said wall, said body member further having a hollow boss extending from said head toward, and having an outer transverse face slidably engaging said carrier member inner wall, and open interiorly to said passage open outer end, said carrier inner wall having an opening affording communication between the interior thereof and the interior of said piston at its inner end portion, and said hollow boss having an opening in a side wall thereof affording communication between the interior thereof and said piston interior at its said inner end portion; and a retainer adjacent the outer end of said carrier member, secured to one of said members and slidably engaging the other of said members whereby said body member is rotatably mounted on said carrier member.

15 30 35 6. In combination with a wrist pin and a connecting rod mounted thereon having a longitudinal bore for the passage therethrough of a cooling and lubricating medium, a piston comprising a hollow body member having an internal transverse wall; a hollow cylindrical carrier member mounted on said wrist pin, having a wall with a face slidably engaging the outer face of said transverse wall; a receiver extending from said carrier member wall, open at its inner and outer ends providing a passage for said medium, said passage being at its outer end slightly spaced from said connecting rod and having its outer end opening in communication with said bore; and a retainer adjacent the outer end of said carrier member, secured to one of said members and slidably engaging the other of said members whereby said body member is rotatably mounted on said carrier member.

40 45 50 55 7. A piston comprising a hollow body member having a head and a skirt, said skirt having a housing portion provided with a cylindrical wall and said head having an integral boss extending to said housing portion provided with a transverse face at its outer end; a hollow carrier member disposed in said housing portion provided with a bore for a wrist pin and a cylindrical wall slidably engaging said housing portion cylindrical wall for free rotative relative movement therebetween and further having at its inner end a transverse wall slidably engaging said boss transverse face for permitting said rotative relative movement and for supporting said head; and a retainer adjacent the outer end of said carrier member, secured to one of said members and slidably engaging the other of said members, permitting said rotative relative movement.
